COVER FOR A BOWL OR THE LIKE

Robert A. Bruce, Corning, N.Y., assignor to Corning
Glass Works, Corning, N.Y., a corporation of New York

Filed Feb. 23, 1968, Ser. No. 10,690

Term of patent 14 years

U.S. Cl. D44—15
Int. Cl. D7—01

Fig. 1

Fig. 2

FIG. 1 is a top plan view of a cover for a bowl or the like embodying my new design; and

FIG. 2 is a cross-sectional view taken along line 2—2 of FIG. 1.

I claim:

The ornamental design for a cover for a bowl or the like, as shown.
